US0D1102904S

(12) **United States Design Patent** (10) **Patent No.:** **US D1,102,904 S**
(45) **Date of Patent:** **** Nov. 25, 2025**

(54) **BOTTLE**

(71) Applicant: **NIAGARA BOTTLING, LLC**,
Diamond Bar, CA (US)

(72) Inventors: **Arif Ahmed Sohel**, Pomona, CA (US);
Joaquin De Leon Del Rosario, San
Dimas, CA (US)

(73) Assignee: **Niagara Bottling, LLC**, Diamond Bar,
CA (US)

(**) Term: **15 Years**

(21) Appl. No.: **29/960,545**

(22) Filed: **Aug. 30, 2024**

Related U.S. Application Data

(62) Division of application No. 29/796,080, filed on Jun.
22, 2021, now Pat. No. Des. 1,046,626.

(57) **CLAIM**

The ornamental design for a bottle, as shown and described.

DESCRIPTION

FIG. 1 is a top perspective view of a bottle.

FIG. 2 is a bottom perspective view of the bottle shown in
FIG. 1.

FIG. 3 is a front view of the bottle shown in FIG. 1.

FIG. 4 is a left side view of the bottle shown in FIG. 1.

FIG. 5 is a right side view of the bottle shown in FIG. 1.

FIG. 6 is a top view of the bottle shown in FIG. 1; and,
FIG. 7 is a bottom view of the bottle shown in FIG. 1.
The dash-dash broken lines represent portions of the article
that form no part of the claimed design. The dash-dot broken
lines represent boundaries of the claimed design and form no
part of the claimed design. Any surfaces inside the bottle
form no part of the claimed design.

1 Claim, 5 Drawing Sheets
